[57] CLAIM

The ornamental design for a free standing tweezer, as shown and described.

DESCRIPTION

FIG. 1 is a front right side perspective view of a free standing tweezer showing my new design;

FIG. 2 is a front elevational view thereof, the rear elevational view being a mirror image;

FIG. 3 is a right side elevational view thereof, the left side; and,

FIG. 4 is a bottom elevational view being a mirror image plan view thereof.

FIG. 1. FIG. 2. FIG. 3.

FIG. 4.
